WITNESS:

INVENTOR
Victor J. Evans.

ATTORNEY

UNITED STATES PATENT OFFICE.

LUCILLE E. PROCTOR, OF CHICAGO, ILLINOIS.

VANITY CASE.

Application filed July 30, 1923. Serial No. 654,686.

To all whom it may concern:

Be it known that I, LUCILLE E. PROCTOR, a citizen of the United States, residing at Chicago, in the county of Cook and State 5 of Illinois, have invented new and useful Improvements in Vanity Cases, of which the following is a specification.

This invention relates to toilet articles and has particular relation to that class of 10 articles known as vanity cases.

An object of the present invention is the provision of a vanity case in which the various cosmetics and toilet accessories are separately contained and arranged so as to 15 be readily accessible, the construction and arrangement being such that the case may be attractively made and may be of a size to be conveniently carried.

With the above and other objects in view, 20 the invention further includes the following novel features and details of construction, to be hereinafter more fully described, illustrated in the accompanying drawings and pointed out in the appended claim.

25 In the drawings:—

Figure 1 is an elevation of a vanity case showing the lid or closure in open position.

Figure 2 is a vertical sectional view with 30 the lid closed.

Figure 3 is a horizontal section.

Referring to the drawings in detail wherein like characters of reference denote corresponding parts, the invention is shown as 35 comprising a casing 10 which is divided by means of a partition 11 into a large compartment 12 and a relatively small compartment 13.

The large compartment 12 is divided by 40 means of transversely arranged partitions 14 into individual compartments 15, the upper or topmost compartment being arranged to contain a removable mirror 16 and a relatively shallow drawer 17 for the reception 45 of small change, tickets and the like. The remaining individual compartments 15 are adapted to contain drawers 18 which are held in closed position by means of catches 19. The catches are secured to the partitions 14 and engage the drawers in such manner that the latter may be held in place 50 but conveniently opened when desired. The drawers 18 may contain various articles for

toilet, such as face powder, rouge, vanishing cream and cold cream and may also 55 contain a chamois, and a powder and rouge puff.

The small compartment 13 is adapted to receive individual containers 20 and 21, the former of which may contain a perfume, 60 while the latter may contain a lip stick. The containers 20 and 21 are arranged end to end and are removably held in place by means of catches 22. A door 23 is hingedly secured to the front of the casing and will 65 act as a closure or cover for the various drawers and containers.

The invention as described and shown will provide an exceedingly useful article which may be conveniently carried about and 70 which will contain practically all of the necessary articles for the toilet.

The invention is susceptible of various changes in its form, proportions and minor details of construction and the right is here- 75 in reserved to make such changes as properly fall within the scope of the appended claim.

Having described the invention what is 80 claimed is:

A vanity case comprising a casing open at the front, a longitudinally disposed partition dividing the casing into a large compartment and a small compartment, spaced partitions arranged transversely across the 85 large compartment and dividing the latter into individual compartments, the outer edges of the partitions being spaced inwardly from the outer adjacent edges of the casing, a drawer for each of the individual 90 compartments, knobs extending outwardly from the drawers, latches extending outwardly from the outer edges of the transverse partitions and engaging the outer edges of the drawers to hold the latter in closed position, said knobs and latches extending into the space defined by the outer edges of the partitions and the adjacent edge of the casing, containers arranged in the small compartment, means for removably holding the 100 containers in place and a cover hinged to one edge of the casing and adapted to close over the front of the drawers.

In testimony whereof I affix my signature.

LUCILLE E. PROCTOR.
